UNITED STATES PATENT OFFICE.

WILSON P. DODSON, OF PHILADELPHIA, PENNSYLVANIA.

FASTENER FOR MEETING-RAILS OF SASHES.

SPECIFICATION forming part of Letters Patent No. 394,962, dated December 25, 1888.

Application filed September 8, 1888. Serial No. 284,879. (No model.)

To all whom it may concern:

Be it known that I, WILSON P. DODSON, a citizen of the United States, residing in the city and county of Philadelphia, and State of Pennsylvania, have invented certain new and useful Improvements in Sash-Holders, of which the following is a specification.

The present invention relates to that class of sash holders or locks which comprise a case or bolt section, a movable bolt mounted in said case, and a keeper with which the end of the bolt engages as it is moved for that purpose.

The invention, however, more particularly relates to means whereby such movable bolt is prevented from accidental movement, and whereby the liability of unlocking the sash-holder is obviated; and it consists in the novel structure hereinafter fully set forth.

The accompanying drawings illustrate the invention as applied to a sash-holder of the class forming the subject-matter of United States Letters Patent Nos. 368,997 and 379,242; but it is obvious that it might be applied to any class of sash-holders employing a movable bolt, which may be accidentally unlocked, in which drawings—

Figure 1 is a perspective view of the under side of the case or bolt section of a sash-holder containing the invention. Fig. 2 is an end elevation of the same. Fig. 3 is a transverse sectional elevation of the same, taken on the line 3 3 of Fig. 1. Fig. 4 is a vertical sectional elevation through the case and keeper, taken substantially on the line 4 4, Fig. 2. Fig. 5 is an elevation of the bolt removed from the case. Fig. 6 is an elevation of the inner side of the bottom confining-plate. Figs. 7 and 8 are modifications of the invention.

The sash holder or lock taken for illustration is substantially like that illustrated in Patent No. 379,242; and it consists, as in said patent, of a case or bolt section, A, having an open socket, d, and extended horizontal flanges e, providing means for securing the case or section to the upper rail of the sash B. Within the socket d is seated a movable bolt, C, having a locking-finger, a, at its outer end and provided with an operative handle, b, that extends through a cam-slot, c, in said socket of the case or bolt section. With this portion of the sash-holder co-operates a keeper, E, that

is secured to the meeting-rail of the other sash, F, and with which keeper the end of the bolt C engages as it is turned for that purpose and 55 by which the two sashes are secured.

In practice it has been found desirable to form the socket d of a size sufficiently large to permit the free movement of the bolt therein as it is moved to lock and unlock the sashes. 60 By reason of this fitting of the bolt in its socket, and in consequence of the fact that its locking-finger a is, preferably, so formed on the end of the bolt that its major portion is all upon one side of the axis of the bolt, it 65 often happens that if the sashes be rattled as the bolt is in its locked position the keeper will tend to bear down upon the finger of the bolt and rock it upon its axis sufficiently to cause the cam-slot, acting upon its 70 operating-handle, to entirely withdraw the bolt from its locked position, and thus unfasten the sashes. In order to obviate this disadvantage in the use of such sash-holders, the device is provided with a locking-detent, H, 75 that is adapted to hold the bolt in its locked position against accidental movement without interfering with the ready operation of the bolt by means of its handle b. The detent H is, in the preferred construction, provided upon the inner side of a bottom confining-plate, D, which detent, when the bolt is moved to its locking position, is adapted to enter a groove, recess, or depression, i, formed in the bolt C, as shown in Figs. 1 and 3. The 80 detent H is preferably a small rib, formed integral with the plate D and extending more or less in the direction of its length, and the groove, recess, or depression i is also formed in the bolt C in the direction of its length and 85 in such position with respect to its locking-finger a that when said locking-finger is in position to engage and lock with the finger E, said groove, recess, or depression will be in position to be engaged by the locking-detent 90 H. In consequence of the construction of the bolt C, hereinbefore pointed out, it follows that any tendency to rock the bolt by the rattling of the sashes, so as to cause the keeper to bear down upon the locking-finger a, will 95 be to cause the bolt to be more firmly pressed in contact with the locking-detent, and be thereby prevented from turning; but it will 100 be seen that as the bolt has sufficient play in

its case to freely pass said locking-detent it will offer no resistance to the proper movement of the bolt when it is operated through its handle *b*.

5 It is obvious that the invention is not limited to the location of the locking-detent and the groove, recess, or depression *i*, so long as the detent bears such relation with respect to the bolt that it will lock the latter against accidental movement. As shown in Fig. 7, the detent *H* is provided on the bolt *C*, while the recess *i*, with which it engages, is provided in the face of the plate *D*. In Fig. 8 the detent *H* is shown as formed on the side of the socket 15 *d*, containing the bolt, the recess *i* being provided in the bolt.

The plate *D* is shown as seated in a recess formed in the under side of the case or bolt section *A*, and held therein against accidental 20 displacement by means of tongues. No claim, however, is herein made to such a plate, as the same forms no part of my invention, but is in fact the invention of another, for which application for Letters Patent is about to be 25 made. So far as the present invention is concerned, however, said plate may be thus secured to the case, as shown in Figs. 1, 2, 3, and 8, or it may be a loose plate simply seated in the recess and held from displacement by 30 the rail of the sash when the case is secured thereto, as shown in Fig. 7.

Without limiting myself to the precise con-

struction and arrangement of parts shown, I claim—

1. A sash-holder having a rotating locking-bolt and a locking-detent arranged to prevent the accidental rotation of the bolt when in its locking position, and to permit the rotation of the bolt under the force of the operating-handle, substantially as described. 35

2. The combination, with the case of a sash-holder having an open socket, a bottom plate, and locking-detent formed on said plate, of a movable bolt mounted in said socket and provided with a recess for engagement with 40 said detent when in its locked position, substantially as described. 45

3. The combination, with the case of a sash-holder having an open socket with a cam-slot therein, a bottom plate, and locking-detent 50 formed on said plate, of a movable bolt mounted in said socket having an operating-handle projecting through the cam-slot of the socket and provided with a recess for engagement with said detent, substantially as de- 55 scribed.

In testimony whereof I have signed my name to this specification in the presence of two subscribing witnesses.

WILSON P. DODSON.
